(57) **CLAIM**

The ornamental design for a gimbal, as shown and described.

DESCRIPTION

FIG. 1 is a perspective view of a gimbal showing my new design;

FIG. 2 is a perspective view viewed from another angle thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of the area "9" shown in FIG. 1;

FIG. 10 is an enlarged view of the area "10" shown in FIG. 1;

FIG. 11 is an enlarged view of the area "11" shown in FIG. 2;

FIG. 12 is an enlarged view of the area "12" shown in FIG. 2; and,

FIG. 13 is an enlarged view of the area "13" shown in FIG. 3.

The evenly spaced broken line are for the purpose of depicting portions of the gimbal and forms no part of the claimed design. The dash dot dash broken line are for the purpose of depicting areas of enlargement and forms no part of the claimed design.

1 Claim, 13 Drawing Sheets
